UNITED STATES PATENT OFFICE.

HORACE W. HOLMES, OF KINGSLAND, ARKANSAS.

WELL-BUCKET.

SPECIFICATION forming part of Letters Patent No. 703,923, dated July 1, 1902.

Application filed February 6, 1902. Serial No. 92,829. (No model.)

To all whom it may concern:

Be it known that I, HORACE W. HOLMES, a citizen of the United States, residing at Kingsland, in the county of Cleveland and 5 State of Arkansas, have invented certain new and useful Improvements in Well-Buckets; and I do declare the following to be a full, clear, and exact description of the invention, such as will enable others skilled in the art 10 to which it appertains to make and use the same.

The invention relates to well-buckets, and more particularly to the well-buckets designed for use in bored or Artesian wells.

15 The object of the invention is to provide a bucket of this character which shall be simple of construction, durable in use, comparatively inexpensive of production, and which will obviate the employment of adjustable troughs, which are now generally used, into which water may be emptied from the bucket, and which will permit of the emptying of the water direct into vessels in either small or large amounts.

20 With this and other objects in view the invention consists of certain novel features of construction, combination, and arrangement of parts, which will be hereinafter more fully described, and particularly pointed out 25 in the appended claims.

In the accompanying drawings, Figure 1 is a perspective view of a bucket embodying my invention, it being partly shown in section. Fig. 2 is a large detail view of the bail. 30 Fig. 3 is a similar view of a fragment of the cross-bar of the bail, the spring-clasp, and the valve-rod; and Fig. 4 is a vertical sectional view through the parts shown in Fig. 3.

In the drawings, 1 denotes a bucket, which 35 consists of a cylindrical shell having at its lower end a valve-seat 2, preferably of wood, and having at its upper end a bail or handle 3. This bail or handle 3 is preferably constructed of a single piece of metal bent as 40 shown in Fig. 2 and formed with a cross-bar 4. The ends 5 of the bail are riveted or otherwise secured to the inner wall of the bucket at its upper end, and the cross-bar 4 is provided with a transverse notch or recess 6. 45 50 7 denotes the valve, adapted to fit the seat 2 and provided with a valve-rod 8, which projects upwardly through the cross-bar 4 and

is adapted to fit into the notch or recess 6. To prevent this rod from falling out of the notch or recess 6, I provide a clasp 9, which 55 consists, preferably, of parallel spring-jaws 10 and 11, having aligned apertures 12, through which the upper end of the rod 8 is passed before the eye or ring 13 is formed thereon. The jaws 10 and 11 are adapted to be slipped 60 over the bar 4 and close the notch or recess 6, so as to hold the rod 8 in vertical position, and thereby hold its valve true to the seat 2.

When it is desired to empty the bucket into a vessel, the upper end of the rod 8 is grasped 65 and raised upwardly, thus unseating the valve at the lower end of the rod and allowing the water to freely pass from the bucket into the vessel placed beneath it. It may be well to state here that by shifting the clasp 9 slightly 70 to one side or in a direction the length of the bar that the rod 8 will be cramped or frictionally held against the walls of the aperture 12 and one of the walls of the notch or recess 6, and thus the rod is retained in its raised position, rendering it unnecessary for the attendant to give further attention to the unfilling of the bucket.

When it is desired to clean the bucket, the clasp may be slipped off the bar 4, the valve 80 removed, thus leaving the bucket freely accessible for cleansing, and when the valve is removed the clasp will be retained on the valve-rod, and thus be prevented from becoming lost or mislaid.

85 From the foregoing description, taken in connection with the accompanying drawings, the construction, mode of operation, and advantages of the invention will be readily understood without requiring an extended explanation.

Various changes in the form, proportion, and details of construction may be made within the scope of the invention without departing from the spirit or sacrificing any of 90 the advantages thereof.

Having thus described my invention, what I claim, and desire to secure by Letters Patent, is—

1. The combination of a bucket having a 100 valve-seat in its lower end, a valve for said seat provided with a rod, a cross-bar secured to said bucket at its upper end and provided with a notch into which the valve-rod pro-

jects, and a clasp for closing said notch and maintaining the valve-rod in a vertical position, substantially as set forth.

2. The combination of a bucket having a valve-seat in its lower end, a valve for said seat provided with a rod, a cross-bar secured to said bucket at its upper end and provided with a notch into which the valve-rod projects, and a clasp for closing said notch or recess for holding the valve-rod in vertical position and having a sliding engagement upon said bar for frictionally locking said rod in an elevated position, substantially as set forth.

3. The combination of a bucket having a valve-seat in its lower end, a valve for said

seat provided with a rod, a cross-bar secured to said bucket at its upper end and provided with a notch into which the valve-rod projects, and a clasp mounted to slide upon said rod and adapted to engage said bar for closing said notch to hold the rod in an upright position, substantially as set forth. 20

In testimony whereof I have hereunto set my hand in presence of two subscribing witnesses.

HORACE W. HOLMES.
